UNITED STATES PATENT OFFICE.

CHARLES S. WILLIAMSON, OF CHICAGO, ILLINOIS.

CONVEYING APPARATUS.

1,213,323.

Specification of Letters Patent. Patented Jan. 23, 1917.

Application filed December 1, 1915. Serial No. 64,591.

To all whom it may concern:

Be it known that I, CHARLES S. WILLIAMSON, a citizen of the United States, residing at Chicago, in the county of Cook and State 5 of Illinois, have invented certain new and useful Improvements in Conveying Apparatus, of which the following is the specification.

This invention relates to propelling devices for conveying apparatus and particularly to a method of arrangement and construction of the driving mechanism for the trucks or wheels upon which the legs of a bridge or crane for conveying coal or the 15 like, are supported.

Bridges for conveying coal, ore or the like, as is well known, are huge structures, often bridging a great width of property as well as many full gage railroad tracks, and are supported upon legs, which in turn are either supported directly upon the axles of the propelling wheels or upon trucks carrying a number of wheels. Great difficulty has been experienced heretofore in the operation of 25 such an apparatus owing to the fact that no certain or positive control of the propulsion has heretofore been possible. The supporting trucks or wheels at the opposite ends of 30 the bridges are spaced a great distance apart and the bridge itself as ordinarily constructed is designed so that one end may be moved in advance of the other to a small extent and therefore, is not capable of withstanding any considerable skewing force so 35 that a comparatively small force which tends to roll one end of the structure along the track and out of exact alinement of the other end can do so. A large number of such bridges have been and continually are being 40 wrecked because wind pressure upon one end of the bridge is generally different from that upon the other end, and the unequal pressure will roll one end of the bridge along the track, skewing the entire structure beyond 45 the intended limits and thereby racking or wrecking it. Furthermore, propelling systems for bridges of this character as heretofore made, generally comprise long trains of gearing or shafting, taking up a great deal 50 of room and involving considerable expense in first cost and up-keep, introducing inevitable lost motion between the meshing gear teeth along the gear trains and worst of all, permitting one end of the bridge to 55 "overhaul" or, under the influence of unequal pressure at the two ends of the bridge, such

as wind pressure, etc., to drive the gearing which is provided to drive each end of the bridge with the result that the bridge skews as above explained. 60

It is a primary object of this invention to do away with any possibility of overhauling the propelling gearing for the trucks or wheels upon which any leg of the apparatus is supported by, making use of a low pitched 65 worm drive therefor.

It is another object of the invention to eliminate a large amount of gearing heretofore used, which as explained, is expensive to construct and operate and introduces in- 70

evitable lost motion, with the greater possibility of serious damage from breakage. It is a further object of the invention to compact and simplify the gearing by the selection and arrangement of its parts, where- 75

by little or no special accommodation is

made necessary across the tracks to provide

room for the gearing which turns the wheels

supporting the legs of the bridge.

It is a still further and important object of 80 this invention to attach the prime mover of my propelling system so as to cut the torque upon the main shaft thereof in half, and making it possible not only to use a lighter 85 shaft, but largely eliminating the heretofore always present danger that the driving gear for one or other leg of the bridge would fail at a critical moment, as when the bridge was being propelled against or was resisting 90 a very heavy wind, with the consequent and often disastrous skewing of the entire structure.

Other objects and advantages of the in- 95

vention in question will appear as the de-

scription to follow proceeds.

In the drawings: Figure 1 is an elevation, partly broken away, of a truck used to support one leg of a bridge and provided with special driving mechanism thereupon. Fig. 2 is an end view of the same. Fig. 3, is a 100 plan view of the same truck. Fig. 4, is a modification, showing a double track instead of a single track as illustrated in the other figures.

I have selected for the illustrative embodiment of my invention, a truck including four or eight supporting wheels (two modifications being shown) equipped with an equalizer frame and designed to receive or support one of the legs of a bridge. This truck, 105 as illustrated, is provided with a special motor drive, it being understood that one truck

is to be employed for each leg of the bridge, the current being thrown simultaneously upon the motors of the various trucks, causing them to act in unison.

1 represents an equalizer frame for supporting the leg of a bridge, the leg of the bridge being pivotally mounted upon the equalizer frame 1 in a manner well known in the art and illustrated, for instance, in the patent to Monroe 1,023,582 of April 16, 1912, this frame being in turn supported upon carriages 2 which are supported upon the axles of propelling wheels hereinafter to be described. Suspended from the equalizer frame 1 by the steel suspension frame 3 (Fig. 1), is an electric motor 4, provided with a small control brake, indicated by 5 the details of which are not herein important. The main shaft 6 of the motor carries thereupon a pinion 7. Arranged adjacent to the motor and extending longitudinally of the truck and firmly mounted in the bearings 8' rigidly secured to the motor casing, is the drive shaft 9, for convenience made in thin sections and connected by flange couplings 8. This shaft is provided with a gear 10 in mesh with the motor gear 7 described, the gear 10 being preferably incased at 11. Upon either end of the shaft 9 are worms 12. These worms mesh with the worm wheels 13 upon shafts 14 and journaled transversely in the carriages 2. It is to be particularly noted that the worms engaged with the worm wheels from below. This makes it possible for me to provide a complete casing 15-16, entirely inclosing the worm and worm wheels firmly mounted upon the equalizer frame 1 and having bearings for the shaft 9 upon either side of the worms 12. The casing 15 and 16 is provided with plugs 17 and 18 to permit the introduction of oil whereby the meshes of the worms and worm wheels run continually in a bath of oil. This would be impossible if the worms meshed, with the worm wheels from above instead of from below as above indicated and is made possible, in part at least, by suspension of the motor.

Upon the ends of shafts 14, opposite from the worm wheels, I provide gears 19, each of which meshes with two gears 20, carried upon extended axles 21 of the supporting and propelling wheels 22, which roll along tracks 23.

55 In the modification shown, in Figs. 1, 2 and 3 a single track is employed upon which are mounted the four propelling wheels 22. It is of course obvious that the same arrangement may be applied where more than 60 one track is employed as indicated in Fig. 4, where two tracks are employed, two propelling wheels 22' being in this instance supported upon the same axles and rolling upon the tracks 23'.

65 It will be apparent that the central sus-

pension of the motor with respect to the drive shaft 9 makes a balanced arrangement whereby the torque upon the shaft will be only half as great (because resisted in opposite directions at its two ends) as if the shaft were driven from one end and the torque were therefore cumulative. This is an important feature of the invention, contributing simplicity and certainty to the operation. It is also to be noted that owing to the worm drive "overhauling" of the driving machinery is impossible, the worm gear train being incapable of operation back from its power delivery end and by any pressure which can occur in use.

I am well aware that other modifications of the same idea might be employed. Thus for light bridges a single shaft centrally driven, might be supported from the sill of the bridge and by means of worm gears drive separate wheels supporting different legs upon the same track, it being by no means necessary in all instances, to employ, as above illustrated, a special truck to support each leg. The special truck, however, is particularly applicable for supporting heavy loads, inasmuch as it greatly augments the distribution of weight over a concrete foundation. It is also clear that a single line shaft might be employed to drive the various subordinate shafts 9 which drive the propelling wheels. I prefer, however, to employ a separate motor in connection with each subordinate driving shaft, whether this driving shaft be employed to drive the wheels of one or more legs of the bridge.

I claim—

1. In a traveling conveying apparatus a frame, a plurality of supporting and propelling wheels mounted in said frame, worm wheels, gearing including meshing gears upon the opposite side of said frame from said worm wheels and connecting the same with said propelling wheels, a worm shaft having worms thereon for driving said worm wheels, a motor suspended from said frame and arranged to drive said worm shaft from a central point between said worms.

2. In a traveling conveying apparatus a frame, having a plurality of supporting and propelling wheels mounted thereon, a plurality of worm wheels, a reduction gearing interposed between said worm wheels and said propelling wheels for driving said propelling wheels, a worm shaft below said worm wheels, a plurality of worms on said shaft, a motor attached to the frame for driving said worm shaft and arranged substantially centrally thereof. 115
120
125

3. In a traveling conveying apparatus, a bridge having legs, a truck to support one of said legs and having a drive shaft thereon, a worm on either end of said shaft, a worm wheel engaged with each of said

worms, a shaft on which each of said worm wheels is mounted, a pinion on each of said last mentioned shafts and propelling wheels, directly driven by said pinions.

- 5 4. In a traveling conveying apparatus, a bridge having legs, a truck to support one of said legs and having a drive shaft thereon, a worm on either end of said shaft, a worm wheel engaged with each of said 10 worms, said worms engaging said worm wheels from below, a shaft on which each of said worm wheels is mounted, a pinion on each of said last mentioned shafts and propelling wheels directly driven by said pinions.

- 15 5. In a traveling conveying apparatus, a bridge having legs, a truck to support one of said legs and having a drive shaft thereon, a worm on either side of said shaft, an independent motor applied to drive said drive shaft at a point between said worms, a worm wheel engaged with each of said worms, a shaft on which each of said worm wheels is mounted, a pinion on each of said last mentioned shafts and propelling wheels directly driven by said pinions.

20 6. In a traveling conveying apparatus, a truck having supporting and propelling wheels thereon having axles extending

through the truck, a motor suspended from said truck, a worm shaft arranged longitudinally of the truck, a plurality of worm wheels arranged above said worm shafts driven thereby, shafts upon which said worm wheels are mounted, intermeshing gears on said shafts and upon the extended axles of the propelling wheels, substantially as described.

25 7. In a traveling conveying apparatus, a bridge having legs, a plurality of wheeled trucks, one on each of a plurality of said legs adapted to support the same, a drive shaft mounted upon each truck parallel to the tread of the truck wheels and having a worm gear at either end, a motor applied centrally to each of said shafts, idler worm wheels driven by said worms and adapted to drive the truck wheels, substantially as described, together with means whereby all of said motors may be stopped and started simultaneously.

In witness whereof, I hereunto subscribe my name to this specification in the presence of two witnesses.

CHARLES S. WILLIAMSON.
